CLAIM

I claim the ornamental design for a water fixture gasket, as shown and described.

DESCRIPTION

FIG. 1 is a top, front and side perspective view of the water fixture gasket of the present invention in a first configuration with the funnel portion extending downwardly from the medial annular space;

FIG. 2 is a bottom, front and side perspective view of the water fixture gasket of the present invention;

FIG. 3 is a side, elevational view thereof, all sides being the same;

FIG. 4 is a top, plan view thereof;

FIG. 5 is a bottom, plan view thereof;

FIG. 6 is a cross-sectional view of the water fixture gasket taken along line 6-6 of FIG. 4;

FIG. 7 is a top, front and side perspective view of the water fixture gasket of the present invention, similar to that of FIG. 1, in a second configuration with the funnel portion folded upwardly into the medial annular space;

FIG. 8 is a bottom, front and side perspective view of the water fixture gasket of the present invention, similar to that of FIG. 2, in a second configuration with the funnel portion folded into the medial annular space;

FIG. 9 is a side, elevational view of thereof, in the second configuration, all sides being the same;

FIG. 10 is a top, plan view thereof, in the second configuration;

FIG. 11 is a bottom, plan view thereof, in the second configuration; and,

FIG. 12 is a cross-sectional view of the water fixture gasket taken along line 12-12 of FIG. 10, in the second configuration.
